Primary Examiner — Michael A Pratt(74) *Attorney, Agent, or Firm* — Haynes and Boone, LLP(57) **CLAIM**

The ornamental design for a hand guard, as shown and described.

DESCRIPTION

FIG. 1 is a front perspective view of a hand guard showing our new design;

FIG. 2 is a rear perspective view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a front side elevational view thereof;

FIG. 8 is a rear side elevational view thereof; and

FIG. 9 is a cross-sectional view thereof taken at line 9-9 of FIG. 1; and,

FIG. 10 is a front perspective view of the hand guard mounted on an example firearm.

The broken lines in the drawings illustrate environmental features and form no part of the claimed design.
